UNITED STATES PATENT OFFICE.

GEORGE A. SCOTT, OF GRAND HAVEN, MICHIGAN.

BOILER CLEANER.

Application filed November 10, 1922. Serial No. 600,075.

This invention relates to a cleaner for boilers particularly designed for removing mud or analogous sediments from within the boiler and discharging it through the blow off line or pipe of the boiler structure.

One object of this invention is to provide a device as specified which may be easily installed in a boiler structure and one which is adjustable to fit various sizes and types of boilers.

Other objects of the invention will appear in the following detailed description taken in connection with the accompanying drawings wherein:

Fig. 1 is a longitudinal section through the mud drum of a boiler, and through the improved cleaner or mud extractor.

Fig. 2 is a cross section taken on the line 2—2 of Fig. 1.

Fig. 3 is a detail section on the line 3—3 of Fig. 2.

Fig. 4 is an enlarged detail section.

Referring more particularly to the drawings, a mud drum 1 of any approved type of boiler is illustrated, which has the blow off pipe or line 2 connected thereto. The improved cleaner is associated with the blow off line or pipe 2 for discharging mud and other sediment therethrough and it comprises a nipple 3 extending into the connecting fitting 3' for threaded engagement therewith. This connecting fitting 3' is carried by a blow-off pipe 2. The nipple 3 has threaded engagement with a coupling 4 mounted upon the main body or pipe 5 of the cleaner. The main body or pipe 5 of the cleaner extends longitudinally within the drum 1 in close proximity to the bottom thereof and is provided with a plurality of longitudinally spaced openings 7 opening out towards the lowermost portion of the drum, as clearly shown in Fig. 1 of the drawings.

The pipe 5 is suspended in the drum by spaced supports 10 which are similar in construction. Each of the supports 10 include a rod member 11 which has a saddle 12 attached to its upper end. This saddle 12 has its opposite ends up-turned as at 13 and these upturned ends are secured to the adjacent wall of the drum in any approved manner. The rod member 11 is connected through the medium of a turn buckle 14 to one end of a rod structure 15 which comprises a rod 16 having a longitudinally ex-

tending recess 18 formed in an end portion thereof for the accommodation of a tongue 19 formed on the rod 17. The tongue 19 is pivotally connected to the rod 16 by a pivot pin 20 so as to permit the rod 16 to be moved pivotally relative to the rod 17 thus permitting the rod 16, turn buckles 14 and rod member 11 to be readily folded upon the rod 17 when placing the device in the drum or when packing the device for shipping purposes. A sleeve 21 is slidably mounted upon the rods 16 and 17 and is limited in its downward movement by means of a pin 22. The sleeve 20 is adapted to extend over the pivot joint between the rods 16 and 17 to lock these rods against pivotal movement when the device is mounted in operative position within the drum. The rod 17 has a saddle 23 attached thereto in any approved manner for engagement with the pipe 5. This saddle is connected to the pipe 5 in any suitable manner.

By adjusting the turn buckles 14, the rods 11 and rod structures 15 can be drawn toward each other to effect a tight connection between the connecting fitting 3' and the adjacent wall of the drum effectively sealing the line of separation therebetween.

In use, when a boiler is "blown out" the pressure of the steam will cause the mud and sediment in the bottom of the drum 1 to be drawn into the pipe 5 and discharged therefrom through the nipple 3 and pipe 2.

It is, of course, to be understood that the invention may be constructed in other manners and the parts associated in different relations and, therefore, I do not desire to be limited in any manner except as set forth in the claim hereunto appended.

Having thus described my invention what I claim is:

In a boiler, the combination with the mud drum and a blow-off pipe thereof, of a conduit suspended in the drum contiguous the lowermost portion thereof and in substantially a horizontal plane, a nipple connected to said conduit and extending vertically through the bottom of the drum, a connecting fitting carried by the blow-off pipe and connected to the nipple and bearing against the adjacent wall portion of the drum, and means for suspending the conduit in the drum, said means including rod members having corresponding end portions secured to a wall of the drum, other rod members,

each of said other rod members including
sectional parts pivotally connected together,
corresponding end portions of said other rod
members being connected to the conduit,
means providing connection between the op-
posite corresponding end portions of said
other rod members and the opposite corre-
sponding end portions of said first mentioned

rod members, the last mentioned means per-
mitting adjustment between said first men-
tioned rod members and said other rod
members in a direction to bind the connect-
ing fitting against said adjacent wall portion
of the drum. 10

In testimony whereof I affix my signature.
GEORGE A. SCOTT.
